CLAIM

The ornamental design for a shoe insole with ornamentation, as shown and described.

DESCRIPTION

FIG. 1 is an isometric view of a shoe insole with ornamentation showing our new design; and,

FIG. 2 is a top view thereof.

The broken lines represent unclaimed borders of the ornamentation regions. The stipple shading in the ornamentation regions represent a contrast of appearance to the areas immediately surrounding the ornamentation regions.

1 Claim, 2 Drawing Sheets

FIG. 1

FIG. 2
